Fraser, Myers & Manley

UNITED STATES PATENT OFFICE

EDWARD G. McCALMONT, OF WEST ENGLEWOOD, NEW JERSEY

DUPLICATOR

Application filed December 8, 1931. Serial No. 579,700.

The present invention relates to duplicators for use in printing a plurality of copies from a stencil sheet and aims to provide certain improvements therein.

- 5 The primary object of the invention is to provide a device of the character described which is simple in construction and operation and highly efficient in use. Another object of the invention is to provide a device of the 10 type described which will produce clear cut and uniformly dark imprints, and one wherein means are provided for picking up a sheet after being imprinted upon, so as to facilitate and expedite the duplicating operation. A 15 still further object of the invention resides in the provision of means whereby the stencil can be quickly attached and removed from the device without soiling the hands of the operator.
- 20 With the foregoing and other objects in view, my invention comprises a supporting frame having a rocker or convex bearing surface upon which is supported a resilient platen or perforated plate adapted to be temporarily deformed by operating pressure so as to cause the stencil supported by the frame to remain in contact with the paper being imprinted for a fractionally longer interval than is customary with the present day 25 conventional devices. I also provide means for causing adhesion of the end of the imprinted sheet to the device upon the completion of the printing operation, whereby said sheet end is raised from the stack and therefore 30 by its removal is facilitated. The invention also embodies other features of novelty which will be apparent from the detailed description which follows, when considered in conjunction with the accompanying drawing 35 showing a preferred embodiment of my invention, and wherein.

Figure 1 is a perspective view of a hand duplicator embodying my invention.

40 Fig. 2 is a side elevation of the duplicator, with parts broken away to show the construction thereof.

Fig. 3 is a section taken substantially along the plane of the broken lines 3-3 of Fig. 2.

45 Fig. 4 is a section taken substantially along the plane of the line 4-4 of Fig. 2.

Referring to the drawing in the various figures, of which the same reference characters are employed to designate their corresponding parts, the duplicator consists of a frame indicated generally by the reference character A, upon which is mounted a resilient perforated metal sheet or platen B, a matting C, a stencil D, pickup means E and stencil tensioning means F.

The frame A may be of any desired or preferred construction, and as is conventional, is formed with a convex or arcuate bearing surface so that in performing the printing operation the device as a whole is rocked over the imprinting surface. In my present construction the frame A consists of a pair of side members a formed of suitably rigid material, said members being disposed and held in parallel relationship by transverse bars a' secured to the top of the side members a, and a connecting bar a² joining the middle points of the bar a' and functioning as a handle for the device. The bottom of the members a are of convex form and covered with a cushioning strip, as indicated at a³, and the ends of each of the members a are preferably straight, as shown at a⁴. The ends and bottom of the frame A are open and are preferably substantially closed by the perforated resilient metal plate B, the end portions b of which are suitably bent upwardly around the ends of the side members a and secured thereto in any convenient way. In mounting the perforated plate B upon the frame, it will be noted, and it is important, that the arcuate or convex portion b' of said plate be spaced from the convex surface of the side members a of the frame in order that said plate may flatten somewhat as downward pressure is applied to the frame when the latter is pressed over a sheet in printing relation thereto. The extent of the spacing between the plate B and the frame will depend upon the character and resiliency of the plate B and the degree of flattening thereof that is desired.

Disposed over the exterior of the plate B is the matting C which serves as an ink pad for the stencil D. Said matting C may be secured to the frame in any desired manner,

and as herein shown is provided at its ends with hooks *c* which engage over the top edges of the plate *B*. Said hook construction on the matting *C*, it will be appreciated, greatly facilitates its mounting and removal from the frame and permits such removal without the necessity of the operator soiling his hands.

The stencil *D*, which is of conventional form, may likewise be mounted or positioned over the matting or ink pad *C* in any desired manner, and as herein shown, the top of said stencil, which is conventionally formed with elongated openings *d*, is positioned over the heads of rivets *G* which are secured to one end wall *b* of the perforated plate, as best shown in Fig. 2. The stencil is then disposed over the matting *C* and its lower end clamped and tensioned at the opposite end of the frame. As herein shown, this clamping and tensioning action is accomplished through the medium of the tensioning means *F*, which consist of a pair of L-shaped brackets *H* mounted on the exterior of the side members *a*, as indicated at *h*, the protruding end of the brackets extending downwardly beyond the end of the frame and providing a limited space between the inner edge of said downwardly-extending arms and the end of the frame, within which space is positioned a tensioning bar *J* formed of any rigid material. To provide the necessary tension whereby said bar *J* will function to satisfactorily hold the end of the stencil in position, there is provided at said end of the frame resilient means, such as a strip of felt or the like *K*, which, by its reactive force after being compressed by the tensioning bar *J*, will tend to hold said bar firmly in place over the end of the stencil.

In the use of duplicating devices of the type described, I have found it highly desirable for promoting the speed with which the duplicating operation is to be performed, to provide means for picking up the end of the imprinted sheet at the end of a printing operation so that the device will be ready for making its imprint upon the next underlying sheet. To accomplish this I employ a suitable means for causing adhesion between the end of the printing surface and the sheet being imprinted upon, so that when the end of the device is raised from the stack of paper being imprinted, either in the course of raising the device bodily or rocking the same upon its convex surface, the end of the imprinted sheet will be raised and thus placed in position for facile removal from the stack. It will be apparent that this inventive concept is capable of various embodiments, and I have herein shown one such embodiment which I have found to be practicable. It consists in disposing across the face of the stencil adjacent the end of the printing surface thereof a flexible strip of material *L*

which may be secured in any suitable fashion to the side walls of the frame, and as herein shown, said strip *L* at its ends is provided with eyelets *1* which engage over headed screws *1'*. Said strip *L* may be provided in its exterior surface at spaced points or entirely across its length with a suitable adhesive which is not too tacky or which will stain the paper being imprinted, it being only necessary that said adhesive have but somewhat greater adhesion for the imprinted sheet than said sheet has for the one beneath it on the stack. Many waxes, gums, resins and the like are suitable for this purpose. To facilitate the mounting and disposition of the adhesive carrying strip and its retention in proper place upon the stencil sheet, the strip *L* is preferably formed of an elastic material.

The use of my present device is quite analogous to that of hand duplicators heretofore known and used, and in practice is as follows: The stencil *D* being suitably prepared, the matting *C* is first coated with ink, either with a brush upon its exterior surface or by placing or brushing the ink over the inner surface of the perforated plate *B*, through which the ink will pass onto the matting. The stencil is then positioned over the matting by first mounting the perforated end over the rivets *G* and then securing the other end with the tension bar *J*. The adhesive-carrying strip *L* is then positioned over the face of the stencil. The device is now ready for use and the printing operation is performed by rocking the frame over the top sheet *M* of a stack of paper *m*, in the course of which rocking action the perforated plate or platen *B*, together with the matting and stencil, will flatten somewhat, whereby the stencil will thus remain in contact with the surface being imprinted upon for a longer interval than would be the case with a construction wherein the convex mounting of the stencil and its supporting elements are rigid. A clear cut and more uniformly dark imprint is thus obtained. At the end of the rocking action and as the device is either lifted bodily from the stack or is rocked backward, the end of the sheet *M* adheres to the strip *L* and is raised, as best shown at Fig. 1, thus facilitating its removal from the stack *m*.

In use it may be found that the ink from the pad *C* finds its way over the interior surface of the plate *B* and tends to move outwardly through the space between the cushion strip *a* of the frame and the plate *B*. To overcome this the inner bottom edges of the members *a* may be provided with felt contact strips *a'* normally pressing against the top surface of the plate *B*.

While I have shown and described a preferred embodiment of my invention and the manner in which the same may be used, I do not wish to be limited to the various details of construction disclosed, since it will be

apparent to one skilled in the art that said details may be modified without departing from the spirit of the invention.

What I claim is:

1. A duplicator comprising a support having printing means mounted thereon adapted to engage over the sheet to be imprinted and a pick-up means for raising the imprinted sheet as the printing means is being removed therefrom.
2. A duplicator comprising a support having printing means mounted thereon adapted to engage over the sheet to be imprinted and a pick-up means, having greater adhesion for the imprinted sheet than two such sheets have for each other, adapted to engage the imprinted sheet at the completing of the printing operation and raise the imprinted sheet as the printing means is being removed therefrom.
3. A duplicator comprising a support having an arcuate or rockable printing surface, and means adjacent the end of said printing surface having a strong adhesion for the sheet being imprinted upon.
4. A duplicator comprising a support having an arcuate or rockable printing surface, and an adhesive carrying means overlying the printing surface adjacent one of the rockable ends thereof.
5. A duplicator comprising a support having an arcuate bearing surface, a stencil disposed over said surface and means on said stencil adjacent one end thereof for causing adhesion thereto of the imprinted sheet, as the support is rocked backward after completing the printing operation.
6. A duplicator comprising a support having an arcuate bearing surface, a stencil disposed over said surface and an adhesive carrying strip disposed across the stencil adjacent one end thereof.
7. A duplicator comprising a support having an arcuate bearing surface, a stencil disposed over said surface and an elastic adhesive carrying strip carried by the support and disposed across the stencil adjacent one end thereof.

In witness whereof, I have hereunto signed
50 my name.

EDWARD G. McCALMONT.
